UNITED STATES PATENT OFFICE

162,558

TABLE

Charles E. Meek, Jr., Warsaw, Ind., assignor to Arnolt Corporation, Warsaw, Ind., a corporation of Indiana

Application July 8, 1949, Serial No. 3,780

Term of patent 14 years

(Cl. D33—14)

To all whom it may concern:

Be it known that I, Charles E. Meek, Jr., a citizen of the United States, residing in Warsaw, in the county of Kosciusko and State of Indiana, have invented a new, original, and ornamental Design for a Table, of which the following is a specification, reference being made to the accompanying drawing, forming a part hereof.

The single figure is a perspective view of a table showing my new design, the appearance from the opposite side and end being similar to that shown.

I claim:

The ornamental design for a table, substantially as shown and described.

CHARLES E. MEEK, JR.
